Patented Mar. 11, 1958

182,304

PAIR OF BINOCULARS

Mario D. Rosiello, Glendora, and Salvatore Merendino, Pasadena, Calif., assignors to David P. Bushnell, Pasadena, Calif.

Application April 22, 1957, Serial No. 45,829

Term of patent 14 years

(Cl. D57—1)

Fig. 1

We claim:

The ornamental design for a pair of binoculars, substantially as shown.
